UNITED STATES PATENT OFFICE.

WILLIAM B. COGGER, OF CLEVELAND, OHIO, ASSIGNOR TO THEODOR KUNDTZ, OF LAKEWOOD, OHIO.

VERTICALLY-ADJUSTABLE SUPPORT.

968,449.

Specification of Letters Patent. Patented Aug. 23, 1910.

Application filed February 23, 1909. Serial No. 479,464.

To all whom it may concern:

Be it known that I, WILLIAM B. COGGER, a citizen of the United States of America, residing at Cleveland, in the county of 5 Cuyahoga and State of Ohio, have invented certain new and useful Improvements in Vertically-Adjustable Supports; and I hereby declare the following to be a full, clear, and exact description of the invention, such 10 as will enable others skilled in the art to which it pertains to make and use the same.

This invention relates to improvements in supporting structures for objects, such, for instance, as desks, tables and seats which are 15 adjustable up and down.

The primary object of this invention is to provide a supporting structure comprising two laterally spaced standards or supports and to readily accommodate a read- 20 justment of the aforesaid adjustable object from the outer side of only one of the said supports.

Another object is to provide simple, durable and efficient mechanism for adjusting 25 the said adjustable object and for securing the latter in the desired adjustment.

Another object is not only to provide a shaft which extends horizontally between and through slots formed in and extending 30 up and down the laterally spaced standards or supports, which shaft forms a member of the adjusting mechanism and is borne by arms depending from and rigid with the aforesaid adjustable object, but to laterally 35 space and brace apart the said arms by a bar which covers and protects the shaft between the said arms without occupying much space.

Another object is to hold the said bar to 40 the said arms without necessitating the use of screws or similar securing devices.

With these objects in view, this invention consists in certain peculiarities of construction, and combinations of parts, hereinafter 45 described, pointed out in the claims, and illustrated in the accompanying drawings.

In the said drawings, Figure 1 is a side elevation of the standards or supports em- 50 ployed in supporting a desk or other object which is to be rendered adjustable up and down relative to the said supports. Fig. 2 is a vertical section on line 2—2, Fig. 1, looking in the direction indicated by the arrow. Fig. 3 is a vertical section on line 55 3—3, Fig. 2, looking in the direction indi-

cated by the arrow. Fig. 4 is a vertical section on line 4—4, Fig. 2, looking inwardly, except that the nut employed in securing the adjustable object in the desired adjustment is shown turned in Fig. 4 to bring the slots or 60 recesses in the periphery of the nut into registry with the slots or recesses in the periphery of a collar interposed between the said nut and the adjacent standard or support. Fig. 5 is a vertical section on line 5—5, Fig. 65 2, looking outwardly. Fig. 6 is a horizontal section on line 6—6, Fig. 2, looking downwardly. Fig. 2 is drawn on a larger scale than Fig. 1, and Figs. 3, 4, 5 and 6 are drawn on a larger scale than Fig. 2. Portions are broken away in Figs. 2 and 6 to 70 reduce the size of the said figures.

In the said drawings, A and A indicate two laterally spaced standards or supports which are rendered stationary in any ap- 75 proved manner and are adapted to be secured to a floor or base (not shown). Each support A is provided with a slot α which extends up and down the said support.

A horizontally arranged shaft B extends 80 between and through the supports A, projecting or extending at the ends through the slots α in the said supports and a suitable distance beyond the outer sides of the said supports. The shaft B is provided exter- 85 nally with a groove b which extends from end to end of the shaft. The shaft B extends loosely through holes e formed in two laterally spaced arms E which depend from and are rigid with the desk or object G 90 which is adjustable up and down on the supports A. The shaft B bears the arms E and consequently the said adjustable object G. The arms E are arranged, one at the inner side of one of the supports A, and 95 the other at the inner side of the other of the said supports.

The supports A are provided at the side edges of the arms E with ribs or guiding members A' which extend up and down the 100 said supports and are arranged to guide the said arms during any readjustment of the adjustable object G.

The slotted portion of each support A is offset outwardly, as at A², to accommodate 105 the location and operation, between the said portion of the said support and the outer side of the adjacent arm F, of a pinion H which is operatively mounted on the shaft B. The operative connection between the 110

said pinion and the shaft (see Fig. 6) is preferably formed by a lug or member *h* formed internally of the pinion and projecting inwardly into and thereby engaging the groove *b* in the shaft. The supports *A* are provided at one and the same side of the shaft *B* with series of vertically spaced teeth arranged to form stationary rack-bars or racks *I* which are in mesh with the pinions *H*. That is the pinions *H* mesh with stationary racks *I* formed on and extending up and down the supports *A* at one and the same side of the shaft *B*.

By the construction hereinbefore described it will be observed that the adjustable desk or object *G* is provided with two laterally spaced depending arms; that the said arms are arranged at the inner sides and adjustable up and down the supports *A*, and that the shaft is operatively provided with pinions meshing with racks formed on the said supports. Obviously therefore the pinions and pinion-bearing shaft move up or down the racks according as the said shaft is turned in the one direction or the other, and the adjustable desk or object *G* is raised or lowered according as the pinions and pinion-bearing shaft are shifted up or down.

30 The shaft *B* is provided at the outer side of the slotted portion of one of the supports *A* with a head *10* which at its inner end forms an inwardly facing shoulder *12* abutting against the laterally outwardly facing surface of the said portion of the said support, and the shaft at the outer side of the slotted portion of the other support bears a collar *L* which abuts against the laterally outwardly facing surface of the said portion of the last-mentioned support and is provided internally with a lug or member *l* which projects inwardly into and thereby engages the groove *b* in the shaft.

The shaft *B* is screw-threaded at the outer end of its collar *L*, and a correspondingly screw-threaded nut *K* is screwed onto the threaded end of the shaft, and obviously by tightening the said nut the collar *L* and the shoulder *12* are caused to be clamped against the outer surface of the slotted portion of the different supports respectively so as to secure the pinion-bearing shaft, and consequently the adjustable desk or object *G*, in the desired adjustment.

55 The collar *L* is preferably circular and provided in its periphery with slots or recesses *13* spaced circumferentially of the collar, and the nut *K* is preferably circular and provided in its periphery with slots or recesses *14* correspondingly spaced circumferentially of the nut. The nut *K* may be loosened by means of a wrench (not shown) having jaws or members adapted to engage the slots or recesses in the periphery of the nut, and upon turning the said nut in loos-

ening it to bring its recesses *14* into registry with the recesses *13* in the collar, as shown in Fig. 4, the said wrench may be shifted inwardly to bring the said jaws or members of the wrench into engagement with the recesses in the collar so that with the same wrench the collar may be turned to rotate the shaft and thereby readjust the adjustable desk or object *G*, and when the said adjustable object has been readjusted to the position desired it is secured in the desired adjustment by again tightening the said nut.

The shaft *B*, being left in the rough, or with an unfinished exterior surface between the arms *E* is, of course, unsightly and therefore I have provided a wooden bar *R* which is nicely finished exteriorly and straddles the shaft between the said arms. The bar *R* is slotted, longitudinally, as at *r*, to accommodate its application to the shaft, and preferably the said bar is so arranged relative to the shaft that the slot *r* is open at the bottom of the bar and under the shaft and the bar depends below the shaft at opposite sides of the shaft. The bar *R* is therefore inverted-U-shaped in cross section. The bar *R* is externally rounded so as to reduce the space which it occupies to a minimum. The bar *R* extends between the arms *E* and is connected and held at its ends to the said arms. The bar *R* therefore laterally spaces and braces apart the arms *E*. The bar *R* is tapered at the ends, as at *15*, to facilitate its entrance at each end into sockets formed by flanges *16* with which the arms *E* at their inner sides are provided, which flanges extend circumferentially of the bar, and the flanges have such arrangement relative to the tapered ends of the bar that the bar upon the assemblage of the parts is tightly embraced or engaged at its ends by the flanges and by the latter securely held to the arms *E* without necessitating the use of screws or similar securing devices in securing the bar to the said arms. The bar *R* it will be observed covers and thereby conceals and protects the shaft between the arms *E*.

To positively prevent displacement of the bar *R* circumferentially of the shaft *B* the flange *16* of one or both of the arms *E* is provided internally with a lug *17* which projects into or engages the slot *r* in the said bar.

A not unimportant feature of the construction illustrated consists in the extension of the groove *b* from the shoulder *12* on one end of the shaft *B* to the opposite extremity of the shaft so that the shaft, upon removing the nut *K* therefrom, is removable endwise from the supports *A*, arms *E*, pinions *H*, collar *L* and bar *R* so as to facilitate renewal or repairing of any of the component parts of the supporting structure illustrated, and obviously the extension of the said

groove to the last-mentioned extremity of the shaft from the said shoulder also facilitates the assemblage of the parts.

What I claim is:—

- 5 1. The combination, with two laterally spaced standards or supports provided each with a slot extending up and down the said support; an object which is adjustable up and down relative to the said supports, said
- 10 adjustable object being provided with two laterally spaced and suitably guided depending arms arranged at the inner sides of the said supports; a shaft extending between and through and supporting the said arms and also extending through the slots in the said supports; means whereby the shaft is raised or lowered according as the shaft is turned in the one or the other direction, and means whereby the shaft is secured in the
- 15 desired adjustment, of a bar extending longitudinally of the shaft between the arms, said bar being provided with a slot which receives the shaft and extends longitudinally of the bar, and members projecting into the
- 20 said slot in the bar and rigid with the said arms.
2. The combination, with two laterally spaced standards or supports provided each with a slot extending up and down the said
- 25 support; an object which is adjustable up

and down relative to the said supports, said adjustable object being provided with two laterally spaced and suitably guided depending arms arranged at the inner sides of the said supports; a shaft extending between and through and supporting the said arms and also extending through the slots in the said supports; means whereby the shaft is raised or lowered according as the shaft is turned in the one or the other direction, and means whereby the shaft is secured in the desired adjustment, of a bar extending longitudinally of the shaft between the arms, said bar being provided with a slot which extends longitudinally of the bar and having such arrangement relative to the shaft that the latter extends through the last-mentioned slot, and flanges formed on the arms and extending circumferentially of the ends of the bar, said flanges being provided internally with lugs projecting into the last-mentioned slot.

In testimony whereof, I sign the foregoing specification, in the presence of two witnesses.

WILLIAM B. COGGER.
